UNITED STATES PATENT OFFICE

133,537

DESIGN FOR A FLAG

Simon L. Waronker, Philadelphia, Pa.

Application March 11, 1942, Serial No. 106,149

Term of patent 3½ years

To all whom it may concern:

Be it known that I, Simon L. Waronker, a citizen of the United States, residing at Philadelphia, in the county of Philadelphia, State of Pennsylvania, have invented a new, original, and ornamental Design for Flags, of which the following is a specification, reference being had to the accompanying drawing, forming part thereof.

The single figure is a face view of a flag, showing my new design.

The drawing is lined for the colors red and blue, the unlined portions representing white.

I claim:

The ornamental design for a flag, substantially as shown and described.

SIMON L. WARONKER.
